UNITED STATES PATENT OFFICE.

JOHN C. McLAUGHLIN, OF NEW YORK, N. Y., ASSIGNOR TO UNDERWOOD TYPEWRITER COMPANY, OF NEW YORK, N. Y., A CORPORATION OF NEW JERSEY.

TYPE-WRITING MACHINE.

No. 878,988.

Specification of Letters Patent.

Patented Feb. 11, 1908.

Application filed October 6, 1905. Serial No. 281,660.

To all whom it may concern:

Be it known that I, JOHN C. McLAUGHLIN, a citizen of the United States, residing in Manhattan borough, city of New York, in the county of New York and State of New York, have invented certain new and useful Improvements in Type-Writing Machines, of which the following is a specification.

This invention relates to the ink ribbon mechanism of typewriting machines, particularly those in which the ribbon is vibrated to cover and uncover the printing point at the type strokes.

The object of the invention is to provide commercially practicable means for permitting the type impressions to be made in ink of different colors at will. This feature of operation is desirable not only in cases where it is desired to emphasize a word by writing it in a color which contrasts with the body of the writing, but also in cases where it is desired to carry both record and copying ribbons upon the machine; the former for writing legal documents and the latter for letters.

In carrying out my invention I employ two ribbons and two vibrators, one for each ribbon, whereby it may be caused to cover and uncover the printing point at the type strokes. For each ribbon I provide a pair of spools, and in the case of front strike writing machines, I prefer to place one pair of spools between the spools of the other pair, so that two spools are mounted edge to edge upon each side of the printing point or at each side of the machine. I provide a winding-mechanism which can be connected to either pair of spools at will, and I also provide means for calling into action that vibrator which carries the ribbon that is wound upon that pair of spools which is associated at the time with the winding mechanism, so that when either ribbon is winding, it is also being vibrated to cover the printing point at the type strokes, while the other ribbon is neither winding nor being vibrated. I also provide means for silencing both the vibrating mechanism and the winding mechanism, whereby stencils may be written.

In the accompanying drawings, in which my improvements are shown applied to the well known "Underwood" front strike writing machine, Figure 1 is a rear elevation of

the ribbon mechanism, showing the front ribbon elevated to cover the printing point, 55 and showing the spools which carry said ribbon connected to the winding mechanism. Fig. 2 is a plan of parts seen at Fig. 1. Fig. 3 is a plan to illustrate the manner of silencing the ribbon vibrators. Fig. 4 is a similar 60 plan to illustrate the manner of operating the vibrator that carries the rear ribbon. Fig. 5 is a sectional side elevation of parts seen at Fig. 1. Fig. 6 is a side elevation of a detail of the means for calling either ribbon- 65 vibrator into action.

Upon the front side of a platen 1 strike types 2, carried upon type bars 3 and adapted to strike through either a front ribbon 4 or a rear ribbon 5, which are of 70 different colors or qualities. The front ribbon 4 is wound upon a pair of spools 6, 7 mounted at opposite sides of the printing point and in front of the platen, with their edges toward the latter and contained in a 75 pair of cups 8, 9. The ribbon which extends between these spools is threaded through a vibrator 10 standing in front of the platen.

The rear ribbon 5 is wound upon a pair of spools 11, 12, carried in cups 13, 14 and 80 threaded through a vibrator 15, which is mounted between the vibrator 10 and the platen. It will be seen that the pair of spools 6, 7 is between the spools 11, 12, so that two spools lie with their respective flanges 85 placed edge toward edge upon each side of the printing point; the rear ribbon 5 extending in rear of the cups 8, 9. In said "Underwood" machines, heels provided upon the type bars press rearwardly a curved universal bar 16, which is fixed upon the front end of a frame or table, 17, the latter carried at its rear end upon upright rock-arms 18 pivoted at 19 and operating a slotted arm 20. The latter engages a pin 21, of a crank 22 90 fixed upon a rock-shaft 23, the latter having at each side of the machine an arm 24 carrying a pawl 25 to engage a ratchet wheel 26 for winding the ribbon. In said machine a shifter bar 27 throws one pawl 25 into action, 100 as at the left hand side of Fig. 1, and the other pawl 25 out of action, as at the right hand side of said figure, thus reversing the longitudinal travel of the ribbon. By means of said pawl and ratchet mechanism, I rotate 105 at each side of the machine a pair of miter

gears 28, 29, the gears 29 fixed upon the lower ends of vertical shafts 30, 31, which at their upper ends carry gears 32, 33. The gear 32 is mounted between gears 34, 35 carried by shafts 36, 37 upon which are mounted the spools 11, 6. The gear 33 is mounted between adjacent gears 38, 39 fixed upon shafts 40, 41 upon which are mounted spools 7, 12. At Fig. 1 the winding gear 32 is being driven by the pawl 25 and is in mesh with the gear 35 to wind the ribbon 4 on the spool 6; while the gear 33 is in mesh with 38 turns idly during the delivery of the ribbon from the spool 7; said gear 33 being disconnected from its pawl 25.

Various means may be adopted for effecting a relative shifting movement of the gears, but that illustrated is in the nature of a contrivance whereby the spools upon either side 20 of the printing point are together shifted either towards or from the spools upon the other side of the printing point, so as to disconnect one pair of spools from the main winding gears 32, 33 and connect the other 25 pair of spools to said gears. To this end the cups 13, and 8 are mounted by means of supports 42 upon a slide 43 guided by studs 44; and the cups 9, 14 are mounted upon a slide 45 guided by studs 46, so that said slides may 30 move transversely of the machine towards and from each other. Such movement is effected by means of a pair of keys 47, 48 mounted upon the ends of a lever 49, which between its ends is fixed upon a rock-shaft 50 35 extending rearwardly and having upon its rear end an upstanding arm 51, which by the depression of said keys is caused to vibrate transversely of the machine. At the upper end said arm 51 loosely engages a bar 52 40 extending across the machine and guided by screw studs 53, said bar being rigidly connected by an arm 54 to the slide 43 which carries the spools at the left side of Fig. 2, so that the vibration of said arm 51 causes a 45 movement of the spool-carrying slide 43 in the same direction. The other end of the operating bar 52 is pivoted by a screw 55 to one end of a lever 56, the other end of which is pivoted at 57 to the other slide 45; said lever 50 being pivoted midway between its ends by means of a screw 58 upon the framework 59 of the typewriting machine, whereby said slides 43 and 45 are caused to move towards each other by depression of the key 47, and 55 away from each other by depression of the key 48 to the positions seen in the drawings. A yielding detent 60 working in notches 61 and 62 in said bar 52 holds the slides with their connections in either of the positions in 60 which they are thus shifted. When the parts are at the other extreme from that seen in the figures, the outer spools 11, and 12 are connected to the winding mechanism, while the inner spools are disconnected therefrom.

65 The ribbon vibrators 10 and 15 are oper-

able by means of the universal bar frame 17 so as to carry up one ribbon, or the other during the printing strokes of the type bars. To the lower end of the vibrator 10 is pivoted the front end of a lever 63; and to the lower end of the vibrator 15 is connected a lever 64. Both levers are pivoted at 65 upon a bracket 66 carried by the usual vertically shiftable platen-supporting rail 67 of the "Underwood" machine, so that the levers together 70 with the vibrators are shifted up and down at the platen-shifting movements of said machine. Said levers are operated by means of a pair of upstanding levers 68, and 69 pivoted at their lower ends at 70, upon some fixed 75 portion of the machine, and having at their upper ends vertical slots 71 and 72 to engage pins 73 and 74 provided upon upstanding arms 75 and 76 of the levers 63 and 64; said slots accommodating the up and down movements of the levers at the case-shift operation. By vibrating either lever 68 or 69, its associated lever 63 or 64 is caused to throw up its attached ribbon vibrator 10 or 15. These levers 68, 69 are actuated by the universal bar frame 17, but only one lever can be actuated at a time; said frame carrying a slide 77 guided by studs 78 and having a toe 79 to engage either lever 68 or 69 according to the adjustment of the slide. At Figs. 90 85 1, 2 and 5, said toe is shown in position to engage the lever 68; while at Fig. 4 it is shown in position to engage the lever 69. When it engages either lever, the other lever stands idle, so that only one vibrator at a 95 time is called into action. The shifting of said slide 77 is effected by a vertical pin 80, extending up to the shift bar 52 and fixed to the latter. The movement of said bar 52 for connecting the winding mechanism to 100 either pair of spools, is also effective through the pin 80 to shift the slide 77 upon the frame 17, so that the toe 79 will operate that lever 68 or 69 which controls the ribbon-vibrator carrying the ribbon which is wound upon 105 the active spools. The pin 80 is loosely connected to the slide 77 by means of a fork 81, so as to accommodate the backward and forward movements of the slide at the operation of the universal - bar frame. Springs 82 110 mounted upon the frame 17 bear lightly against the rear edges of the levers 68 and 69 to restore them to normal positions after actuation.

By shifting the bar 52 to a midway position, so that the detent 60 occupies an intermediate notch 83, the toe 79 will be brought opposite the space between the levers 68, 69 as at Fig. 3, thereby silencing both the ribbon vibrators 10 and 15; while all the gears 115 34, 35, 38 and 39 will stand out of mesh with the winding gears 32, 33; thereby silencing the winding mechanism, so that stencils may be written without any activity whatever upon the part of either ribbon.

Variations may be resorted to within the scope of my invention and portions of my improvements may be used without others.

Having thus described my invention, I claim:

1. In a typewriting machine, the combination with two pairs of ribbon spools all placed with their respective flanges edge toward edge, so that the ribbon extending between the spools are superposed, of adjustable means operable by all the keys for causing the ribbon upon either pair of spools to cover the printing point at every type stroke.

2. In a front strike writing machine having a type-operating mechanism, the combination with a platen, of two pairs of ribbon spools all mounted with their respective flanges placed edge toward edge in front of the platen so that the ribbons extending between the spools are superposed, one pair of spools mounted between the spools of the other pair, means for winding either spool of either pair, and means for enabling the type-operating mechanism to cause the ribbon upon either pair of spools to cover and uncover the printing point at the type strokes.

3. In a typewriting machine having a type-operating mechanism, the combination with two pairs of spools, of means for winding either spool of either pair while the spools in the other pair remain stationary, and means for enabling the type-keys to cause the ribbon upon either pair of spools to vibrate during the type strokes to cover and uncover the printing point.

4. In a typewriting machine, the combination with a platen and types mounted to strike upon the front side thereof, of two pairs of spools mounted with their respective flanges edge toward edge in front of the platen, one pair between the spools of the other pair, means for causing the ribbon upon either pair to vibrate to cover and uncover the printing point during the type strokes, and means for winding the ribbon back and forth upon either pair of spools while the spools in the other pair remain stationary.

5. In a typewriting machine having a type-operating mechanism including type keys, the combination with two pairs of spools, of a spool-winding mechanism, means for causing either pair of spools to be operated by said winding mechanism while the other pair remains stationary; and means for enabling the type-keys to cause the ribbon upon either pair of spools to cover the printing point at the type strokes.

6. In a typewriting machine, the combination with two pairs of spools, of a spool-winding mechanism, a shifting device for connecting either pair of spools to said winding mechanism, and means connected to said shifting device for causing to cover the printing point that ribbon which is carried by the

spools which are connected to the winding mechanism.

7. In a typewriting machine, the combination with two pairs of spools, of a spool winding mechanism, a shifting device for connecting either pair of spools to said winding mechanism, and means operable simultaneously with said shifting device, for causing to cover and uncover the printing point at the type strokes that ribbon which is carried by the spools which are connected to the winding mechanism.

8. In a typewriting machine, the combination with a platen and types mounted to strike upon the front side thereof, of two pairs of spools mounted with their respective flanges placed edge toward edge in front of the platen, two spools at each side of the printing point, one pair of spools between the spools of the other pair, two vibrators for causing the ribbons to cover and uncover the printing point, a spool winder at each side of the printing point, means for effecting co-operation between said winders and either pair of said spools, means for bringing into action the vibrator which is associated with the spools with which the winders co-operate, and means for reversing the direction of rotation of said winders.

9. In a typewriting machine, the combination with a platen and types mounted to strike thereon, of two pairs of spools mounted with their respective flanges placed edge toward edge, one pair of spools between the spools of the other pair, so that two spools are at each side of the printing point, gears upon all of said spools, a reversible winding gear at each side of the printing point, each winding gear being mounted between two adjacent spool gears, and means for effecting shifting movements between the spool gears and the winding gears.

10. In a typewriting machine, the combination with a platen and types mounted to strike thereon, of two pairs of spools mounted with their respective flanges placed edge toward edge, one pair of spools between the spools of the other pair, so that two spools are at each side of the printing point, gears upon all of said spools, a reversible winding gear at each side of the printing point, each winding gear being mounted between the two adjacent spool-gears, and means for shifting both pairs of spools laterally in such a manner as to effect disconnection of the winding gears from one pair of spools and connection of said winding gears to the other pair of spools.

11. In a typewriting machine, the combination with a platen and types mounted to strike thereon, of two pairs of spools mounted with their respective flanges placed edge toward edge, one pair of spools between the spools of the other pair, so that two spools

are at each side of the printing point, gears upon all of said spools, a reversible winding gear at each side of the printing point, each winding gear being mounted between the two adjacent spool-gears, and means for shifting both pairs of spools laterally in such a manner as to effect disconnection of the winding gears from one pair of spools and connection of said winding gears to the other pair of spools; a pair of ribbon-vibrators, one for each ribbon, and means connected to said shifting means for rendering one vibrator effective and the other ineffective.

12. In a typewriting machine, the combination with a platen and types mounted to strike thereon, of two pairs of spools placed with their respective flanges placed edge toward edge, one pair of spools between the spools of the other pair, so that two spools are at each side of the printing point, a carrier upon which are mounted the spools at one side of the printing point, a carrier upon which the other spools are mounted, means connecting said carriers to cause them to move simultaneously in opposite directions, gears upon the spools, and winding gears one at each side of the printing point between the spool gears.

13. In a typewriting machine, the combination with a platen and types mounted to strike thereon, of two pairs of spools placed with their respective flanges placed edge toward edge, one pair of spools between the spools of the other pair, so that two spools are at each side of the printing point, a carrier upon which are mounted the spools at one side of the printing point, a carrier upon which the other spools are mounted, means connecting said carriers, to cause them to move simultaneously in opposite directions, gears upon the spools, and winding gears one at each side of the printing point between the spool gears; means for detaining said carriers in different positions, two ribbon vibrators mounted at the printing point, one for each pair of spools, and connections between said vibrators and said carriers such that when the carriers are shifted in either direction, the corresponding vibrator is brought into effective action while the other vibrator is rendered ineffective.

14. In a typewriting machine having a type-operating mechanism, the combination with two ribbon vibrators and two pairs of ribbon spools for carrying the ribbons threaded through said vibrators, of means controlled by the type-operating mechanism for vibrating the ribbons to cover and uncover the printing point, a finger-piece, and means controlled by the latter for both rendering either vibrator effective and the other vibrator ineffective and also causing the winding of the ribbon which is threaded through the effective vibrator.

15. In a typewriting machine having a

type-operating mechanism and type-keys, the combination with means for supporting two ribbons and means for causing either ribbon to wind while the other remains stationary, of means operated by the type-keys for causing the winding ribbon to be vibrated to cover and uncover the printing point at the type strokes.

16. In a typewriting machine, the combination with means for supporting two ribbons, of reversible winding means, a finger-piece, means controlled by said finger-piece for causing either ribbon to be wound by said winding means while the other ribbon remains stationary, two vibrators for causing the ribbon to cover and uncover the printing point at the type strokes, and means also controlled by said finger-piece for calling into action the vibrator which carries the winding ribbon and rendering the other vibrator ineffective.

17. In a typewriting machine having a platen shifting up and down, the combination with a universal bar frame, of a lever pivoted upon the framework and engaged by said frame and having a vertical slot, and a ribbon-vibrating lever shiftable up and down with said platen and having a pin in engagement with said slot.

18. In a typewriting machine, the combination with a universal bar frame, of a plurality of levers directly engageable by said frame, and a plurality of ribbon vibrators one behind the other and operable by said levers; means being provided for silencing either vibrator at will.

19. In a typewriting machine, the combination with a universal bar frame, of a plurality of levers, shiftable means for enabling said frame to engage either of said levers at will, ribbon vibrators, and levers connected to said vibrators and operable by said levers.

20. In a typewriting machine, the combination with a winding-mechanism and two pairs of spools, of a shifting member for causing coöperation of said winding mechanism with either pair of spools at will, a pair of ribbon vibrators for the ribbons upon said spools, a universal bar, levers connected to said vibrators and operable by said frame, and means connected to said shifting device for causing either of said levers to be operated by said universal bar, so that the latter will be caused to vibrate that ribbon which is carried by the spools that coöperate said winding-mechanism.

21. In a typewriting mechanism, the combination with winding mechanism and two pairs of spools, one pair mounted between the spools of the other pair so that two spools are at each side of the printing point, a bar extending transversely of the machine and having at its ends means for connecting said winding mechanism with either pair of spools, a finger-piece for said bar, means for detain-

ing said bar in different positions, two ribbon vibrators, levers for operating said vibrators, a universal bar, and shiftable means mounted upon said universal bar and loosely connected to said transverse bar, for operating said levers.

22. In a typewriting machine, the combination with two slides, of two spool receiving cups mounted upon each of said slides, connections between said slides to enable them to recede from and approach each other, spindles mounted in said slides, one in each of said cups, for receiving the spools, gears upon said spindles, and a winding gear mounted upon the framework of the machine between adjacent spindle gears.

23. In a typewriting machine having a type-operating mechanism, the combination with two pairs of ribbon spools, of means for enabling the type-operating mechanism to cause the ribbon on either pair to vibrate to cover and uncover the printing point at the type strokes, and for silencing the ribbon vibrating means at the type strokes, at will.

24. In a typewriting machine having a type-operating mechanism, the combination with two pairs of ribbon spools, of means for winding the ribbon back and forth upon either pair of spools, and means for enabling the type operating mechanism to cause the ribbon on either pair to vibrate to cover and uncover the printing point at the type strokes, and for silencing the ribbon vibrating means at the type strokes, at will.

25. In a front strike writing machine having a type-operating mechanism the combination with two pairs of ribbon spools placed with their respective flanges placed edge toward edge, of means for winding either spool of either pair, means for silencing the winding means, and means for enabling the type - operating mechanism to cause the ribbon upon either pair of spools to cover the printing point at the type strokes while the ribbon upon the other pair of spools remains idle.

26. In a front strike writing machine having a type - operating mechanism and a platen, the combination of two pairs of ribbon spools mounted with their respective flanges placed edge toward edge in front of the platen, one pair between the spools of the other pair, means for winding either spool of either pair, means for silencing the winding means, and means for enabling the type - operating mechanism to cause the ribbon upon either pair of spools to cover and uncover the printing point while the ribbon upon the other pair of spools remains idle.

27. In a typewriting machine having a type-operating mechanism, the combination with two pairs of spools, of means for winding either spool of either pair while the spools in the other pair remain stationary,

means for silencing the winding means, and means for enabling the type-operating mechanism to cause the ribbon upon either pair of spools to cover the printing point or to remain out of use at the type strokes, at will. 70

28. In a typewriting machine having a type-operating mechanism, the combination with two pairs of spools, of means for winding either spool of either pair while the spools in the other pair remain stationary, 75 and means for enabling the type-operating mechanism to cause the ribbon upon either pair of spools to cover and uncover the printing point, or both ribbons to remain out of use during the type strokes, at will. 80

29. In a typewriting machine having a platen, types mounted to strike upon the front side thereof, and a type-operating mechanism, the combination of two pairs of spools mounted with their respective flanges placed 85 edge toward edge in front of the platen, one pair between the spools of the other pair, means for enabling the type-operating mechanism to cause the ribbon upon either pair to vibrate to cover and uncover the printing 90 point or both ribbons to remain out of use during the type strokes, and means for winding the ribbon back and forth upon either pair of spools while the spools in the other pair remain stationary. 95

30. In a typewriting machine having a type-operating mechanism, the combination with two pairs of spools, of a spool-winding mechanism controlled by said type-operating mechanism, and means for causing either 100 pair of spools to be operated by said winding mechanism while the other pair remains stationary and means for silencing the winding means.

31. In a typewriting machine having a type-operating mechanism, the combination with two pairs of spools, of a spool-winding mechanism, controlled by the type-operating mechanism, and means for causing either pair of spools to be operated by said winding 110 mechanism while the other pair remains stationary; vibrators controlled by the type-operating mechanism for causing the ribbon upon either pair of spools to cover the printing point, and means for simultaneously 115 silencing both the vibrators and the winding means.

32. In a typewriting machine, the combination with two pairs of spools, of a spool-winding mechanism, a shifting device for 120 connecting either pair of spools to said winding mechanism, vibrators connected to said shifting device for causing to cover the printing point that ribbon which is carried by the spools which are connected to the winding 125 mechanism, and means controlled by said shifting device for silencing both the winding mechanism and the vibrators.

33. In a typewriting machine, the combination with two pairs of spools, of a spool 130

winding mechanism, a shifting device for connecting either pair of spools to said winding mechanism, and means operable simultaneously with said shifting device, for either 5 causing to cover and uncover the printing point at the type strokes that ribbon which is carried by the spools which are connected to the winding mechanism, or for causing both ribbons to remain out of use during the 10 type strokes.

34. In a typewriting machine, the combination with a platen and types mounted to strike upon the front side thereof, of two pairs of spools mounted with their respective 15 flanges placed edge toward edge in front of the platen, two spools at each side of the printing point, one pair of spools between the spools of the other pair, two vibrators for causing the ribbons to cover and uncover the 20 printing point, a spool winder at each side of the printing point, means for effecting coöperation between said winders and either pair of said spools, means for bringing into 25 action the vibrator which is associated with the spools with which the winders coöperate, or causing both ribbons to remain idle during the type strokes, and means for reversing the direction of rotation of said winders or silencing them both.

35. In a typewriting machine, the combination with a platen and types mounted to strike thereon, of two pairs of spools mounted with their respective flanges placed edge toward edge, one pair of spools between 30 the spools of the other pair, so that two spools are at each side of the printing point, gears upon all of said spools, a reversible winding gear at each side of the printing point, each winding gear being mounted between two 35 adjacent spool gears, and means for effecting shifting movements between the spool gears and the winding gears, so as either to cause one of the spools to wind, or to silence the 40 winding mechanism.

36. In a typewriting machine, the combination with a platen and types mounted to strike thereon, of two pairs of spools mounted with their respective flanges placed edge toward edge, one pair of spools between 45 the spools of the other pair, so that two spools are at each side of the printing point, gears upon all of said spools, a reversible winding gear at each side of the printing point, each winding gear being mounted between the 50 two adjacent spool-gears, and means for shifting both pairs of spools laterally in such a manner as either to effect disconnection of the winding gears from one pair of spools and connection of said winding gears to the other 55 pair of spools, or to silence the winding mechanism, at will.

37. In a typewriting machine, the combination with a platen and types mounted to strike thereon, of two pairs of spools mounted 60 with their respective flanges placed edge to-

ward edge, one pair of spools between the spools of the other pair, so that two spools are at each side of the printing point, gears upon all of said spools, a reversible winding gear at each side of the printing point, each 70 winding gear being mounted between the two adjacent spool-gears, and means for shifting both pairs of spools laterally in such a manner as to effect disconnection of the winding gears to the other pair of spools or to 75 silence the winding devices, at will; a pair of ribbon-vibrators, one for each ribbon, and means connected to said shifting means for rendering one vibrator effective and the other ineffective, or to silence both vibrators, at 80 will.

38. In a typewriting machine, the combination with a platen and types mounted to strike thereon, of two pairs of spools placed with their respective flanges placed edge 85 toward edge, one pair of spools between the spools of the other pair, so that two spools are at each side of the printing point, a carrier upon which are mounted the spools at one side of the printing point, a carrier upon 90 which the other spools are mounted, means connecting said carriers, to cause them to move simultaneously in opposite directions, gears upon the spools, and winding gears one at each side of the printing point between the 95 spool gears; means for detaining said carriers in different positions, two ribbon vibrators mounted at the printing point, one for each pair of spools, and connections between said vibrators and said carriers such that when 100 the carriers are shifted in either direction, either one vibrator is brought into effective action while the other vibrator is rendered ineffective, or both vibrators are silenced.

39. In a typewriting machine, having a 105 type-operating mechanism, the combination with two ribbon vibrators actuated by the type-operating mechanism, and two pairs of ribbon spools for carrying the ribbons threaded through said vibrators, of a finger-piece, and means operable by the latter for both rendering either vibrator effective and the other vibrator ineffective and also causing the winding of the ribbon which is threaded through the effective vibrator, or 110 silencing both the winding means and the vibrators.

40. In a typewriting machine having a type-operating mechanism, the combination with means for supporting two ribbons and 115 means for causing either ribbon to wind while the other remains stationary, of means operated by the type-operating mechanism for causing the winding ribbon to be vibrated to cover and uncover the printing point at the 120 type strokes, and means for silencing both the winding means and the vibrators.

41. In a typewriting machine having a type-operating mechanism, the combination with means for supporting two ribbons, of 125

- reversible winding means, a finger-piece, means controlled by said finger-piece for causing either ribbon to be wound by said winding means while the other ribbon remains stationary and for silencing the winding means, two vibrators controlled by the type-operating mechanism for causing the ribbon to cover and uncover the printing point at the type strokes, and means also controlled by said finger-piece for calling into action the vibrator which carries the winding ribbon and rendering the other vibrator ineffective, and also for silencing both vibrators simultaneously. 65
42. In a typewriting machine, the combination with a winding mechanism and two pairs of spools, of a shifting member for causing coöperation of said winding mechanism with either pair of spools or silencing all the spools at will, a pair of ribbon vibrators for the ribbons upon said spools, a universal bar, levers connected to said vibrators and operable by said frame, and means connected to said shifting device for causing either of said levers to be operated by said universal bar, so that the latter will be caused to vibrate that ribbon which is carried by the spools that coöperate said winding mechanism, or for silencing both vibrators. 70
43. In a typewriting machine, the combination with two pairs of spools and a gear for each spool, said spools placed with their flanges extending edge toward edge, of two winding wheels, means for connecting the winding wheels to either pair of spool gears, and means for reversing the direction of winding of the wheels. 75
44. In a front strike writing machine, the combination with two winding members, one at each side of the printing point, of two pairs of spools in front of the platen and connectible in alternation with said winding gears; said spools placed with their perspective flanges extending towards one another. 80
45. In an ink-ribbon mechanism, the combination of spools for two ink-ribbons; independent vibrators for said ribbons; means for operating either of said vibrators singly; ribbon driving devices connectible with a spool of either ribbon; a finger-lever, and connections from said lever for shifting the vibrator operating means from one to the other vibrator and for disconnecting the driving devices from one and connecting them to the other set of ribbon spools. 85
46. In an ink-ribbon mechanism, the combination of sets of spools for two ribbons; independent vibrators for said ribbons; vibrator operating mechanism provided with a member shiftable to connect said mechanism with either vibrator singly; ribbon-driving devices connectible with either set of spools singly, and a member shiftable to effect disconnection of either set of spools from and connection of the other set of spools with said ribbon-driving devices. 90
47. In an ink-ribbon mechanism, the combination of sets of spools for two ribbons; independent vibrators for said ribbons; vibrator operating mechanism provided with a member shiftable to connect said mechanism with either vibrator singly; ribbon-driving devices connectible with either set of spools singly, a member shiftable to effect disconnection of either set of spools from and connection of the other set of spools with said ribbon-driving devices, and hand operated means for simultaneously moving both of said shiftable members. 95
48. In an ink-ribbon mechanism, the combination of separate sets of spools for different ribbons; independent vibrators for said ribbons; a to and fro moving member for actuating said vibrators; means for connecting said member with and disconnecting it from said vibrators to operate them singly; ribbon driving devices; a member shiftable to connect the ribbon driving devices with said sets of spools singly; and a key for operating said shiftable member and said connecting and disconnecting means. 100
49. In a typewriting machine, the combination with two pairs of spools and a gear for each spool, of two winding gears, means for connecting the winding gears to either pair of spool gears, and means for reversing the direction of winding of the ribbons. 105
50. In an ink-ribbon mechanism, the combination of spools for two ink-ribbons; vibrators for said ribbons; means for operating either of said vibrators singly; ribbon driving mechanism connectible with a spool of either ribbon; and means for connecting said driving mechanism and said operating means with a spool and the vibrator respectively of any of said ribbons. 110
51. In a ribbon-mechanism, the combination of spools for different ink-ribbons; independent vibrators for said ribbons for covering and uncovering the printing point; means shiftable from one to another of said vibrators for actuating said vibrators singly; means shiftable from one to another of the sets of said ribbon spools, for feeding endwise the ribbon in use; and mechanism for shifting the vibrator operating and ribbon feeding mechanisms simultaneously. 115
52. In a front-strike typewriting machine, the combination of shafts; pairs of spools for independent ribbons on said shafts, one ribbon on each pair of spools; means for guiding one ribbon behind the other; and independent vibrators for said ribbons to cause them, singly, to cover and uncover the printing point. 120
53. In a typewriting machine, the combination with type-operating devices and two pairs of ribbon spools, of two ribbons

wound upon said spools, one ribbon upon each pair of spools, and means for enabling all the type-operating devices to vibrate either ribbon to cover and uncover the printing-point at the type strokes, at will.

54. In a typewriting machine, the combination with type-operating devices and two pairs of ribbon spools, of means connected to all the keys for winding the ribbon back and forth upon either pair of spools, and means for enabling all the type-operating devices to cause the ribbon on either pair of spools to vibrate to cover and uncover the printing point at the type strokes, at will.

55. In a typewriting machine, the combination with type-operating devices, of two ribbons, shiftable means for enabling either ribbon to cover and uncover the printing point at the type strokes, two pairs of spools upon which said ribbons are wound, one ribbon upon each pair, and means connected to said shiftable means to cause the spools of the active ribbon to wind.

56. In a typewriting machine, the combination with type-operating devices, of two ribbons, two pairs of spools carrying said ribbons, one ribbon upon each pair, shiftable means for winding either spool of either pair while the spools in the other pair remain stationary, and means connected to said shiftable means for enabling all the type-operating devices to cause the winding ribbon to vibrate to cover and uncover the printing point at the type strokes.

57. In a typewriting machine, the combination with a platen and type-operating devices, of two pairs of spools, one spool in each pair mounted at each side of the printing point, spool-winding means mounted at each side of the printing point, means for effecting coöperation between the winding means and either pair of spools, two vibrators, one for each ribbon, and shiftable means for enabling all the type-operating devices to reciprocate at each type stroke the vibrator which carries the winding ribbon.

58. In a typewriting machine, the combination with a platen and type-operating devices, of two pairs of spools, a ribbon upon

each pair, gears upon all of said spools, reversible winding gears, and means for effecting a shifting movement between the spool gears and the winding gears to cause either ribbon to wind.

59. In a typewriting machine, the combination with a platen and type-operating devices, of two pairs of spools, a ribbon upon each pair, gears upon all of said spools, reversible winding gears, means for effecting a shifting movement between the spool gears and the winding gears to cause either ribbon to wind; a vibrator for each of said ribbons, and means for enabling all of the type-operating devices to operate that vibrator which carries the winding ribbon, while the other vibrator remains stationary.

60. In a front strike writing machine, the combination with a platen and type-operating devices, of two upright revoluble shafts, one on each side of the printing point, two ribbons, and two pairs of spools, one pair for each ribbon, the spools in each pair being located one on each side of the printing point, means to connect either shaft to either of the spools on the same side of the printing point to wind the same, vibrators for said ribbons, and means operable by all the type-operating devices and connectible to said vibrators to cause the winding ribbon to cover and uncover the printing point at the type strokes.

61. In a typewriting machine, the combination with a platen and type-operating devices, of two pairs of ribbon spools, the spools in each pair being mounted one at each side of the printing point, gears for all of said spools, a winding gear at each side of the printing point and connectible to either of the spool gears, means for effecting shifting movements between the spool gears and the winding gears and to cause any one of the four spools to wind singly, and means operable by all the type-operating devices to vibrate the winding ribbon to cover and uncover the printing point at the type strokes.
